WILHELM DAUMANN, OF HAMBURG, GERMANY, ASSIGNOR TO C. H. F. MÜLLER,
RÖNTGENRÖHRENFABRIK, OF HAMBURG, GERMANY, A CORPORATION OF GERMANY.

ELECTRON TUBE.

Application filed June 9, 1924, Serial No. 718,755, and in Germany June 11, 1923.

My present invention relates to electron tubes of the type employing a filamentary electrode in conjunction with a co-operating electrode having a relatively large surface.

5 The object of this invention is to improve the construction of tubes of this type, particularly such as are intended for operation at high voltages, at which there is considerable danger of injury and even rupture of the 10 filament.

According to my invention, the filamentary electrode is given the form of a loop or bow situated partly or entirely within the co-operating electrode which has a concave 15 surface directed toward the filamentary electrode, and a peculiar relation, explained in detail hereinafter, is established between the said two electrodes, to protect the filament against injury, and to prevent accidental contact of the two electrodes.

The invention will now be explained in detail with reference to the accompanying drawings, in which Figs. 1 and 2 are two sections, taken axially of the tube, but at 20 right angles to each other, showing a typical form of my invention, together with dotted lines indicating certain important relations which constitute the basis of my improved arrangement; Figs. 3 and 4 are axial sections, taken at right angles to each other, illustrating a second form of my invention; Fig. 5 is an axial section of a third embodiment, which is also illustrated in partial plan view in Fig. 6 and in a detail perspective 25 view in Fig. 7; Figs. 8 and 9 are respectively an elevation and a plan, with parts in section, of another form of my invention, in which the large-surfaced electrode is cylindrical; and Figs. 10 and 11 are respectively 30 an axial and a transverse section of a form of construction of the same general type as that shown in Figs. 8 and 9.

Referring particularly to Figs. 1 and 2, I will describe this example of my invention as follows:

One of the electrodes, which constitutes the anode in the use of the device, is formed as a dished body 1 of spherical curvature,

while the other electrode, which in use will be the cathode, consists of an arched or 50 looped filament 2, of any suitable conducting material, the ends of said filament being secured to conducting supports 3, as indicated at 4. The large-surfaced electrode or anode 1 is made of sheet-metal or other 55 suitable material. It will be understood that the two electrodes with the supports 3 are generally located within an evacuated bulb of any usual or approved construction; this remark will apply to all the forms of 60 my invention illustrated in the drawings; for the sake of clearness, the bulb and the manner of connecting the electrodes with it have been only indicated in a general way in Fig. 1, and any person skilled in this 65 art will be able to provide a suitable way of arranging the said parts within such a bulb. It will be noted that the major portion of the filament bow 2 lies within the dished anode 1, the concave surface of which is directed toward said filament. It will also be understood that, generally, the filament is adapted for connection with a battery or other source of electricity located exteriorly 70 of the electron tube, so that by the passage of a current from such external source, the filament may be heated to the temperature best adapted for the particular effect to be produced in each individual case. Now, in the 75 operation of the electron tube, when the filament is subjected to forces tending to deform it, there are two main requirements: First, whatever deformation or distortion the filament may undergo, it must never come in contact with the opposing electrode. 80 Second, the main resultant of the forces acting on the filament should be such as to tend to give it an axial position substantially as shown, in other words, the tendency of such forces should be to pull the filament 85 toward the axis (the central vertical line in Figs. 1 and 2) rather than to deflect it laterally from said axis. Now referring to Fig. 1 it will be obvious, assuming the filament to be perfectly flexible, that the far- 90

95thest points the filament could reach, within

the plane of Fig. 1, will lie on an ellipse such as the filament will describe if the fixed points 4 are used as the foci of the ellipse. This ellipse is indicated by the dotted line 5 E, and it will be obvious that the major radius a of this ellipse will be equal to one-half of the length l of the filament, while its minor radius b will be equal to

$$10 \quad \sqrt{\frac{l^2}{4} - e^2},$$

where the distance between the two fixed filament ends 4 is designated as $2e$. If such 15 an ellipse is then rotated about the axis connecting the two points 4, 4, the ellipsoid thus described will be the locus containing all the farthest points which the filament secured at 4, 4 can reach, assuming (as 20 stated above) such filament to be perfectly flexible, substantially like a string. Now, the condition that the filament shall not be able to touch the electrode 1 is evidently fulfilled by arranging said electrode entirely 25 outside of the ellipsoid above defined. In the projection Fig. 2 the outline of said ellipsoid would appear as a circular line E'. If the anode 1 were of an ellipsoidal shape parallel to the ellipsoid mentioned 30 above, it would exert a uniform action or attraction at all points on the filament, and there would be no tendency to give the latter a definite position. In order that there may be a tendency to give the filamentary electrode an axial position, the concave surface of the anode 1 is made to approach the surface of the said ellipsoid more closely at the axial portion than at other points or portions, or in other words, the 35 radius of curvature of said anode surface will be greater than that of the said ellipsoid; this will be clear, particularly from Fig. 1. In practice, with an anode of the general dished form shown in Figs. 1 to 5, 40 I have found that satisfactory results are obtained if the dimension h , which I may term the height of the filament arc or bow (said dimension being but slightly smaller than the minor radius b of the aforesaid 45 ellipsoid) is made smaller than the distance of any point of the straight line or base 4-4 from the nearest point of the concave surface of the anode 1. The curve G in Fig. 1 represents the limit case in which the 50 distance from any point of the said base line 4-4 to the nearest point of the curve G is constant, being equal to the dimension h .

The anode and the filamentary cathode are in axial alignment, their axis coinciding 55 with the longitudinal axis of the vacuum tube or electron tube.

The construction illustrated by Figs. 3 and 4 differs from the one shown in Figs.

1 and 2 simply by having the anode 5 bell-shaped, with a curled flange, the filamentary 65 cathode 6 having its loop or bow within the anode, and the relations as to filament length and position of the anode relatively thereto, being governed by the same rules as explained above in connection with Figs. 1 70 and 2.

When the electron tube is intended for heavy duty, and particularly for currents of great strength, incandescent filaments of considerable length are required. Instead 75 of employing a single filament of great length, it is advisable in such cases, for practical reasons, to employ a plurality of cathode loops or bows, the size of the anode surface being increased correspondingly. 80 In certain prior constructions, a flat or plane anode has been used; this, however, would present material difficulties in the case of a plurality of cathode loops facing such a plane anode, since the loops facing the marginal portion of the anode would lie in the region of strongly unsymmetrical fields and would thus be deflected or bent quite considerably. Furthermore, the cathode rays 85 issuing from these marginal loops would not strike the anode portions lying next to them, but would deviate and reach points not constructed to receive the impact of such rays. Stray rays of this character are 90 liable to injure the tube by perforating the glass bulb, especially during the evacuating operation. Again, in the special case of 95 using the electron tube for the generation of X-rays, rays straying from the intended path will evidently reduce the efficiency or 100 power of the tube, by diminishing the number of rays that become effective or available.

From the above consideration, the advantage of giving the anode a shape such that it 105 will enclose or surround the cathode loop or loops at least partly, will be apparent. The special construction adopted by me also neutralizes any forces tending to twist the individual loops; this result is another advantage of the particular proportioning of certain dimensions as explained above in connection with Figs. 1 and 2.

Several forms of my invention in which a 110 plurality of filament loops are employed in conjunction with a curved anode surrounding them partly or entirely, are shown in Figs. 5 to 11.

In the construction illustrated by Figs. 5, 115 6, and 7, the anode 7 (Fig. 5), shown of spherical curvature, encloses or surrounds the loop portions of the three wires or filaments 8, 9, and 10, which are connected in series as will be understood best from Fig. 7. 120 One end of the filament 8 is secured at 11 to the conducting support 13, while to the other 125

conducting support 14 is secured, at 12, one end of the filament 10; the other ends of these filaments 8, 10, are secured to the ends of the third or middle filament 9. The 5 three filaments are disposed in planes which are substantially radial with respect to the spherically-curved anode 7. The relation of each of the three filaments to said anode is determined according to the same rules or 10 proportions as those explained above in connection with the construction shown in Figs. 1 and 2.

When a very great filament length is required, a construction such as shown in Figs. 15 8 and 9 may be used with advantage. In this case the anode has the shape of a cylinder 15 extending continuously around the space within which the filaments are located. For instance, a rod 16 consisting of a refractory insulating material, (quartz being suitable), is arranged axially within said cylinder 15 and constitutes a carrier for a 20 series of spirally-disposed filament loops 17 secured to successive portions of said rod, for instance by means of metal collars 18. The filaments are conductively connected with each other, so that they may be brought to incandescence by means of a current supplied through the leads 19, 20. The individual loops 17 project toward the cylindrical anode surface, so that for each loop the maximum of the electrostatic attraction will be effective at the apex of the loop, in a direction toward the axis of the tube, along 30 the axis or "height" of the loop. Should there be any unsymmetrical action of the forces tending to bend the loops lengthwise of the cylinder, these can never lead to any dangerous distortion of the plane of the loop, for the reason that for each of the loops the conditions explained above are observed, the "height" of each loop being smaller than the distance of any point of its base from the inner surface of the cylindrical anode 15; also, the special relation of the anode surface to the ellipsoid described by each of the filament loops if it were swung about its attached ends, would hold in this case in the same manner as I have explained above in 40 connection with Figs. 1 and 2.

These remarks will also apply to the further form of my invention illustrated by Figs. 10 and 11. Here the individual filament loops 21 are arranged in two sets, in an axial plane, the cylinder anode 22 being of the same type as the anode 15 of Figs. 8 and 9, and a rod or carrier 23 extending axially within the anode, the bases of the filaments being parallel to the anode axis. The several loops 21 are secured to collars 24 surrounding the central carrier rod 23, and form two sets or series arranged on opposite sides of the carrier. At the upper or inner

end of the carrier, the farther ends of the last filaments or loops of the two sets are 65 connected with each other as shown in Fig. 10; the other end of one set is connected with the lead 25, and that of the other set with a lead 26, while the several loops of the same set are connected in series. 70

Electron tubes of the type set forth herein may be used for the production of X-rays, or for any other purpose for which tubes of this character are adapted. It will be understood that when cylindrical anodes are employed, as in Figs. 8 to 11, such anodes would be open at least at one end, the upper end being shown open in Figs. 8 and 10.

Various modifications may be made without departing from the nature of my invention as set forth in the appended claims. 80

I claim:

1. An electron tube including an anode having a concave surface and a filamentary cathode having a loop located within the anode, the ends of said filament being fixed, and the concave anode surface lying entirely outside of a rotation ellipsoid whose axis of rotation coincides with a line connecting the points at which the ends of the filament are 85 fixed, and the axial section of said rotation ellipsoid exhibiting an ellipse whose major radius is equal to one-half of the length of the filament, and whose minor radius is 90 equal to 95

$$\sqrt{\frac{l^2}{4} - e^2},$$

where l designates the length of the filament, and $2e$ the distance between said fixed points. 100

2. An electron tube including an open anode having a concave surface and a filamentary cathode having a loop located within the anode, the ends of said filament being fixed, and the height of the filament 105 loop being smaller than the distance of any point of the straight line connecting said fixed ends, from the nearest point of the concave surface of said anode.

3. An electron tube including an anode having a cylindrical concave surface, a carrier disposed axially with respect to said anode, and a plurality of filamentary looped cathode elements supported by said carrier and located at different points of its length, 115 each of said looped elements being of a height smaller than the distance of any point of the straight line connecting the ends of such element, from the nearest point of the concave surface of said anode. 120

4. An electron tube including an anode having a cylindrical concave surface, a carrier disposed axially with respect to said anode, and a plurality of filamentary cathode elements each having fixed ends supported by said carrier, the several elements 125

being located at different points of the carrier's length, and the concave anode surface lying entirely outside of the ellipsoidal surfaces which the filamentary elements would 5 describe if swung about their fixed ends.

5. An electron tube including an open anode having a concave surface and a filamentary cathode having a loop located with-

in said anode, the ends of the filaments being fixed, and the central portion of said 10 loop being at a smaller distance from the concave anode surface than any other portion of the filament.

In testimony whereof I have signed this specification.

WILHELM DAUMANN.
